TOY SUPPORT

Herman A. Feigelman, Paterson, N. J.

Application February 28, 1946, Serial No. 650,945

5 Claims. (Cl. 46—32)

1

This invention relates to supporting or display platforms utilized in connection with toys or other articles.

It is an object of the present invention to provide an efficient, economical and practical platform or the like for supporting and/or displaying articles such as, for example, toy figures.

It is a further object of the present invention to provide a platform and/or support made of a single blank and having a plurality of folded and cut-out sections adapted to hold articles per se or mountings upon which articles may be mounted.

It is yet a further object of the present invention to provide a mounting or stand for the article co-operating with a platform or display base adapted to maintain such mounting or stand in position.

These and other objects of the invention will be in part obvious from the annexed drawing and in part hereinafter indicated. In connection therewith is the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they may embody the same by the numerous modifications in structure and relation contemplated by this invention, a drawing depicting certain forms of the invention has been annexed as a part of this disclosure, and in such drawing, like characters of reference denote corresponding parts throughout all the views, of which:

Fig. 1 is a plan view of a blank made in accordance with the invention;

Fig. 2 is a view of the blank of Fig. 1 set up to constitute a platform and having applied thereto a mounting or support for a figure, shown in broken lines, another figure shown in broken lines, being supported by said platform;

Fig. 3 is a plan view of a mounting or support cooperable with said platform, drawn to a larger scale;

Fig. 4 is a side elevation of the support of Fig. 3, shown in erected position; and

Fig. 5 is a plan view of the support of Fig. 3 in erected position and assembled on the base.

Referring more particularly to the drawing, the numeral 10 indicates a blank having the longitudinal score lines or creases 11 connecting the side edges 12 and 13; The longitudinal fold line or crease 14 is aligned with the side edge 15.

2

By means of the crease 11 a side flap 16 is provided and by means of the crease 14 a side flap 17 is provided. The fold line or crease 18 which is intermediate and aligned with the end edges 19, 20 of the respective flaps 16, 17 produces the end flap 20a. A similar end flap 21 is provided, which is joined to the body portion 22 by the fold line or crease 23.

A body extension 24 is hinged to the body portion 22 by the fold line 25, the blank being cut at 26 and 27 to separate side-ends of body extension 24.

Cut 27 is preferably made so that a notch 28 is formed in body portion 22 and a corresponding projection 29 in extension 24.

Body portion 22 is provided with a plurality of maintaining or sustaining means generally indicated by the numeral 30, each of said means comprising oppositely disposed spaced apart side flaps 31 hinged to the body portion 22 by the fold lines 32 and an end flap 33 hinged to body portion 22 by the fold line 34.

Flap 33 is preferably made arcuate at its free end 35, the contiguous edges thereto of flaps 31 being preferably likewise arcuate.

Retaining means, such as that indicated by the numeral 40, may be formed at one or more locations on the body portion 22. Each retaining means 40 is formed of a pair of T-shaped flaps 41 each having an edge of the head portion 43 thereof integral with the body 22 along the fold line 42. The relatively narrow stems 44 of the T-shaped flaps 41 extend toward each other and confront along the cut 44a. The flaps 41 then form tabs 42a on each of the opposite sides of the stems 44.

The body extension 24 is provided with one or more preferably irregularly shaped openings, 50, 51 and the parallel spaced apart fold lines 52, 53, and 54.

In setting up the platform or display stand for use, the longitudinal flaps 16 and 17 are folded backwards against the underface of body portion 22. The flaps 16 and 17 constitute a bottom for the maintaining means 30 and 40, so that an article such as the figure F (shown in broken lines) may have its base B inserted under flaps 31 and 33 and over the bottom thus formed by the flaps 16, 17. It will also be possible to make one of the flaps, say 17, wider than the other so that the flaps may overlap when in folded position.

It is understood that in lieu of having the sustaining means 30 and 40 support the figure or article directly, a mounting or stand may be provided which would be sustained by the means 30

or 40 and the figure or article to be displayed mounted on such member.

One suitable mounting member is shown in Figs. 3 and 4 and generally indicated by the numeral 60, which is adapted to be sustained in operable position by the means 40. Member 60 has a central section 61 tapering towards both its ends, the latter having hinged thereto by the fold line 61a, the end tabs 62. Tabs 62 preferably extend endwise from the extremities of central portion 61. Portion 61 is provided with a preferably irregularly shaped opening 63 and spaced apart parallel fold lines 64. Member 60 is folded along the lines 61a and 64 and inserted on platform P with the tabs 62 under the portions 43 of flaps 41 and under tabs 42a with the reduced extensions or stems 44 of the flaps 41 projecting within the space formed between the spaced apart vertical sides 65, it being understood that the reduced portions of member 61, shown here on a larger scale than sustaining means 40 (Fig. 1), will just fit between the two wide portions 43 of the latter, thus securely locking the mounting 60 to the platform. As is seen in Fig. 2 the character Fa shown in broken lines and representing a horse, is retained in folded member 60 such that the lower middle portion of the horse is received in the opening 63. The legs of the character Fb shown in broken lines and representing a soldier mounted on the horse Fa, extend through the lateral portions 66 of opening 63.

Referring to the body extension 24, it will be noted that in the example shown in the drawing, openings 50, 51 are substantially identical with the opening 63 of Fig. 3. So that, whereas member 60, which is locked in position by means of tabs 41, 42 is utilized for the purpose of supporting or retaining Fa and Fb, the said characters may be mounted directly on the body extension 24. For this purpose the body extension 24 is folded along the lines 25, 52, 53 and 54, the sections 24a of Fig. 1 becoming the vertical walls 24a of Fig. 2. The tab extension 29 rests on the body 22 when the platform is folded as clearly seen in Fig. 2.

From the foregoing it is evident that there has been provided herein a folding support comprising two blanks, one of said blanks comprising a main body section 22, an auxiliary body section 24 hinged to main body section 22, lateral sections 16, 17 hinged to main body section 22, end sections 20a, 21 hinged to the main body section, the main body section having a plurality of portions 30, each of said portions comprising a pair of spaced parallel tabs 31, hinged to the main body section 22 and a tab 33, hinged to the main body section disposed adjacent to and at a right angle with respect to parallel tabs 31, the adjacent edges of said tabs being substantially arcuate, as indicated at 35, main body section 22 further having at least one other portion 40 comprising a pair of opposed T-shaped tabs 41 hinged to the main body section, main body section 22 having extensions 42a adjacent said T-shaped tabs 41, the auxiliary body section 24 having spaced parallel score lines 52 and at least one opening 50 or 51 provided at said score lines and extending beyond said score lines, the other blank 60 having spaced parallel score lines 64 and an opening 63 provided at and extending beyond the

score lines 64, blank 60 cooperating with tabs 41 and extensions 42a.

Although the drawing, and the above specification disclose the best mode in which I have contemplated embodying my invention, I desire in no way to be limited to the details of such disclosure, for in the further practical application of my invention many changes in the forms and proportions may be made as circumstances require or experience suggests without departing from the spirit of the invention within the scope of the appended claims.

Having thus described my invention what I claim as new and desire to secure by Letters Patent is:

1. A support comprising a platform, a pair of T-shaped flaps, each of said flaps including a head and a stem extending at right angles to said head member, said flaps being oppositely disposed with the heads thereof being hingedly connected to said platform, a pair of oppositely disposed tabs on said platform extending towards the stems of said flaps between the heads of the latter, and a mounting including oppositely extending end tabs on the lower end thereof adapted to engage under said first mentioned tabs and under the heads of said flaps for securing said mounting to said platform.

2. A support comprising a platform, a pair of T-shaped flaps, each of said flaps including a head and a stem extending at right angles to said head and from the center thereof, said flaps being disposed with the stems thereof extending towards each other with the heads thereof being hingedly connected to said platform, a pair of oppositely disposed tabs on said platform extending between the heads of said flaps on opposite sides of the stems thereof, and a mounting including means on the lower end thereof engaging under said tabs and under the ends of the heads of said flaps for securing said mounting on said platform.

3. A support according to claim 2, wherein said means on the lower end of said mounting includes a pair of oppositely extending tabs, the central portions of said mounting tabs engaging under said platform tabs, and the opposite end portions of said mounting tabs engaging under the heads of said T-shaped flaps.

4. A support according to claim 2, wherein said mounting is formed of an inverted U-shaped member, and said means includes oppositely extending tabs on the lower ends of the side legs of said member adapted to engage under said platform tabs and the heads of said T-shaped flaps, the stems of said flaps engaging between the side legs of said member to thereby lock said mounting upon said platform.

5. A support according to claim 4, wherein said member is formed with an article receiving opening in the upper end thereof.

HERMAN A. FEIGELMAN.
